(57) **CLAIM**

(22) Filed: **Nov. 27, 2019**

The ornamental design for a semi-integrated sensor monitor for attachment to an inhaler, as shown and described.

(51) LOC (14) Cl. **29-02**

DESCRIPTION

(52) U.S. Cl.
USPC **D24/110**

FIG. 1 is a back perspective view of a semi-integrated sensor monitor for attachment to an inhaler;

(58) **Field of Classification Search**

FIG. 2 is an opposite back perspective view of the semi-integrated sensor monitor for attachment to an inhaler;

USPC ... D24/107, 108, 110, 110.1-110.5, 127, 164;
D29/108
CPC A61M 15/0085; A61M 15/0005; A61M
11/005; A61M 11/00; A61M 11/02; A61M
11/04; A61M 5/087; A61M 5/0871; A61M
5/091; A61M 5/097; A63B 23/18; A61M
15/00; A61M 15/0065; A61M 15/0091; A61M
15/0021; A61M 15/0026; A61M 15/008;
A61M 15/007

FIG. 3 is a top perspective view of the semi-integrated sensor monitor for attachment to an inhaler;

See application file for complete search history.

FIG. 4 is a bottom perspective view of the semi-integrated sensor monitor for attachment to an inhaler;

(56) **References Cited**

FIG. 5 is a side view of the semi-integrated sensor monitor for attachment to an inhaler;

U.S. PATENT DOCUMENTS

FIG. 6 is an opposite side view of the semi-integrated sensor monitor for attachment to an inhaler;

D424,236 S * 5/2000 Reed D27/163
D441,071 S * 4/2001 Attolini D24/110
D512,777 S * 12/2005 Beisner et al. D24/110
D549,341 S * 8/2007 Ross et al. D24/164

FIG. 7 is front view of the semi-integrated sensor monitor for attachment to an inhaler;

FIG. 8 is a back view of the semi-integrated sensor monitor for attachment to an inhaler;

FIG. 9 is a top view of the semi-integrated sensor monitor for attachment to an inhaler; and

FIG. 10 is a bottom view of the semi-integrated sensor monitor for attachment to an inhaler.

In all of the figures, the broken lines having a short dash pattern show an inhaler or portion thereof, and form no part of the claimed design.
